UNITED STATES PATENT OFFICE.

JESSE ALEXANDER, OF NEW YORK, N. Y.

DESIGN FOR A REGISTER AND INDICATOR-CASING.

No. 38,205.

Specification for Design.

Patented Aug. 28, 1906.

Application filed July 3, 1906. Serial No. 324,708. Term of patent 14 years.

To all whom it may concern:

Be it known that I, JESSE ALEXANDER, a citizen of the United States, residing at New York, county of Kings, State of New York, have invented a certain new, original, and ornamental Design for a Register and Indicator-Casing, of which the following is a specification, reference being had to the accompanying drawings, forming part thereof.

Figure 1 is a perspective view of a register and indicator-casing of my design, the same

being taken looking down upon it. Fig. 2 is a perspective view of the same from the right-hand side.

I claim—

The ornamental design for a register and indicator-casing, substantially as shown.

JESSE ALEXANDER.
